US00D671876S

(12) **United States Design Patent**
Roura

(10) **Patent No.:** **US D671,876 S**
(45) **Date of Patent:** **** Dec. 4, 2012**

(54) **VEHICLE WHEEL RIM**

(75) Inventor: **Cesar Muntada Roura**, Pfaffenhofen an der Ilm (DE)

(73) Assignee: **Audi AG**, Ingolstadt (DE)

(**) Term: **14 Years**

(21) Appl. No.: **29/419,837**

(22) Filed: **May 2, 2012**

(30) **Foreign Application Priority Data**

Nov. 2, 2011 (EM) 001 941 444-0005

(51) **LOC (9) Cl.** **12-16**

(52) **U.S. Cl.** **D12/209**

(58) **Field of Classification Search** D12/204-213;

301/37.101, 64.101, 65, 64.201

See application file for complete search history.
